UNITED STATES PATENT OFFICE.

IGNATZ GONYK, OF LJUBLJANA, YUGOSLAVIA.

SCYTHE.

Application filed August 20, 1924, Serial No. 733,205, and in Austria August 21, 1923.

In scythes, and the like hitherto known the premature wear of the blade due to repeated sharpening has been avoided by arranging on the blunt main scythe-blade by means of 5 special covering rails an interchangeable steel blade, said rail being rigidly connected with the latter blade.

The invention consists in the fact that the covering rail and the interchangeable blade 10 are not rigidly connected as heretofore; these two parts are, however, made separately and are connected by a clamping action of the rail which is slid over the interchangeable blade, said rail being provided 15 with holes which correspond to the rivet heads on the main scythe blade, longitudinal slots being also provided in the rail and each of said slots is arranged to communicate with its adjacent hole while the walls 20 thereof are inclined toward said hole. The improvement of the arrangement over the known devices consists in an increased fastening effect owing to the pressure which is exerted by the covering rail on the two 25 blades and which is due to the inclining of the walls of the slots. Hitherto no such pressure had been applied in the known devices.

The invention is illustrated by way of 30 example in the accompanying drawings in which Fig. 1 is a side view of the scythe comprising a dull main blade and a sharp steel blade fastened thereon by means of a covering rail; Fig. 2 shows the different 35 parts on an enlarged scale and Fig. 3 is a longitudinal section on line A—B of Fig. 1 on an enlarged scale; Fig. 4 is an enlarged longitudinal sectional detail showing the improved clamping means, and Fig. 5 is a fragmentary top plan detail of a part of the rail.

As in some of the known devices the main scythe blade *a* only serves as support for the working blade and is therefore quite blunt; it is provided with rivets *b* which 45 engage by means of transverse slots *d* with the sharpened strip *c* of steel plate which

is about 0.25 mm. thick. This strip *c* acts as the cutting blade. A fastening rail *e* is passed over the heads of the rivets *b* having holes *f* corresponding to said rivets. The 50 rail is also provided with a plurality of longitudinal slots *g* each of which has one end communicating with the adjacent opening while the walls of the slots are beveled as at 55 *g'* and inclined toward said opening and enable the rail to exert a pressure on the blade *c* increasing when the rail is shifted thus fastening the interchangeable blade on the main blade *a* by friction. In order to improve the fastening action the scythe blade 60 *a* is moreover provided with a rib *h* which prevents the blade *c* from projecting for a non-uniform amount beyond the blade *a*, the former being brought into abutment with the rib *h* when being mounted and a projection *i*, the latter on the outer edge of the blade *a*, by which the point *a'* of the blade *a* is brought into alignment with the edge of the blade *c*. The blade *a*, rivets *b* and covering or fastening rail *e* or only the two latter 70 members may be made of aluminium or the like to reduce the weight.

What I claim is:

A device of the character described including a main blade, a series of headed 75 fasteners carried thereby, a sharpened strip engageable with the fasteners, a covering rail provided with a series of holes for receiving the corresponding headed fasteners and with a series of longitudinal slots, each of said 80 slots having one end communicating with the adjacent hole the walls of the slots being beveled and inclined towards said hole, whereby when said rail is shifted the headed fasteners ride upon the inclined walls of 85 the slots and exert a wedging and clamping action on the strip, substantially as and for the purposes set forth.

In testimony whereof I have signed my name to this specification.

IGNATZ GONYK.
